(57) **CLAIM**

The ornamental design for a speaker, as shown and described.

DESCRIPTION

FIG. 1 is a perspective view of a speaker showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left, bottom perspective view thereof.

FIG. 9 is an enlarged detail view of area 9 shown in FIG. 1.

FIG. 10 is an enlarged detail view of area 10 shown in FIG. 3; and,

FIG. 11 is an enlarged detail view of area 11 shown in FIG. 8.

The broken lines in FIGS. 1, 3, and 8 illustrating boundaries of areas of enlargement form no part of the claim. The broken lines in FIGS. 9, 10, and 11 illustrating the boundaries of the figures form no part of the claim. All other broken lines in the drawings depict portions of the speaker that form no part of the claimed design.

1 Claim, 11 Drawing Sheets
